UNITED STATES PATENT OFFICE

ARTHUR F. PYM, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY

WORK POSITIONING MEANS

Application filed November 2, 1928. Serial No. 316,846.

This invention relates to work-positioning means for use in the manufacture of shoes and is herein illustrated, in one aspect, as embodied in a device adapted to be detachably applied to a last for use in the manufacture of turn shoes to insure proper positioning of the shank pieces in the shoes.

The sole of a turn shoe is usually reinforced at the heel and shank portions by a combined heel pad and shank stiffener, commonly known as a turn shank piece, consisting of a filler member of leather or fiber shaped to fit the inside contour of the heel and shank portions of the shoe, and a metallic stiffener strip which is secured to the under side of the filler member. In accordance with the usual practice the turn shank piece is placed within the shoe after the shoe has been turned and while the shoe is on the second last and it is desirable for various reasons properly to locate the shank piece relatively to the shoe and to hold the shank piece against accidental displacement until it has been permanently secured in place. In United States Letters

25 Patent No. 1,482,201, granted January 29, 1924, on application of the present inventor, there is disclosed a last for use in turn shoe making having special fittings adapted to function when the last is used as a second last

30 to position a shank piece within a turn shoe in the process of manufacture and to hold the shank piece in place during the heel-seat lasting operation. The special fittings just referred to comprise two pins permanently

35 associated with the last and arranged to project above the bottom of the heel portion of the last to enter two holes formed in a turn shank piece, the pins being depressible below the surface of the last bottom so as not to interfere with the use of the last as a first last when occasion may require.

One object of the present invention is to provide simplified and less expensive means for fitting a last to insure proper positioning and holding of a shank piece when the last is

used as a second last in the manufacture of turn shoes, while still permitting the last to be used as a first last whenever desired.

With this object in view, one feature of the present invention consists in the provision of a device for use in positioning a shoe part on a last which, as herein shown, comprises a thin narrow strip adapted to extend cross-wise of a last between the last bottom and a shank piece, said strip having at one side a pair of pins spaced lengthwise of the strip for entering spaced holes in the bottom of the last and having a pair of pins spaced lengthwise of the strip at the opposite side thereof for entering spaced holes in the shank piece, thereby to position the shank piece in a desired lengthwise, lateral and angular relation to the last. Preferably, in order that the device may be temporarily retained in operative position on a last, the strip bearing the pins is made of spring metal and is so shaped as to enable the pins which enter the holes in the last to be cramped in the holes and thus frictionally held therein.

The invention will now be more particularly described by reference to the accompanying drawing and thereafter defined in the claims.

In the drawing

Fig. 1 is a perspective view of a last with a turn shank piece positioned and held in place thereon by the use of means constructed in accordance with the present invention;

Fig. 2 is a sectional view taken along the line II—II of Fig. 1;

Fig. 3 is a perspective view of the shank piece positioning device detached;

Fig. 4 is a detail view showing the shank piece positioning device in side elevation together with a portion of a last in section and illustrating the manner of applying the device to the last; and

Fig. 5 is a detail sectional view taken along the line V—V of Fig. 4.

Referring to the drawing, a last A is pro-

vided with two holes 10 (Fig. 2) formed in metal bushings 12 inserted in the heel portion of the last bottom. A turn shank piece B (Fig. 1) consisting of a combined heel 5 pad and filler piece C, and a metallic strip D, is provided with two holes 14 which extend through the heel portion of the filler piece. The holes 10 in the last are spaced apart widthwise of the last while the holes 10 14 in the shank piece are spaced apart a corresponding distance widthwise of the shank piece and are arranged to be coaxially alined with the holes in the last when the shank piece is properly positioned on the last.

15 The device herein shown for positioning the shank piece on the last consists of a thin, longitudinally curved strip 16 of spring metal provided with two pins or projections 18 upon one side of the strip for entering the holes 10 in the last, and with two pins or projections 20 upon the opposite side of the strip for entering the holes 14 in the shank piece. As shown, the pins 18 are located respectively near the opposite ends of the strip 20 16 and the holes 10 are spaced apart transversely of the last bottom so that the axis of curvature of the strip will extend in the direction of the axis of transverse curvature of the last bottom. Moreover, the pins 18 25 extend at right angles to the surface of the strip while, to facilitate convenience in manufacture, the pins 20 are coaxially alined with the pins 18. Each of the pins 18 and 20 is formed with a rounded free extremity for 30 facilitating the entrance of the pin into its respective hole in the last or in the shank piece. As best shown in Fig. 4, the strip 16 is curved or arched lengthwise to such an extent that when the shank piece positioning device is detached from the last the radius of curvature of the strip is somewhat shorter than the radius of transverse curvature of the portion of the last bottom to which the strip is to be applied. The pins 35 40 or projections 18 are so arranged relatively to each other on the strip 16 that when the pins are introduced into the holes 10 in the last the strip 16 will be straightened somewhat, causing the resiliency of the strip to 45 cramp or bind the pins against the inner sides of the holes 10 in the last thus, in effect, clutching or gripping the last so that the shank piece positioning device is firmly held in place thereon. Thus when the shank piece 50 55 positioning device is secured in place on a last the strip will conform to the transverse curvature of the last bottom so that it will lie throughout its length in contiguous relation to the surface of the last bottom.

60 After the shank piece positioning device has been applied to a last a turn shank piece such as the shank piece B is placed on the last over the positioning device with the holes 14 in the shank piece receiving the pins 20 65 on the positioning device. The pins 20 serve

to locate the shank piece on the last, as shown in Fig. 1, so that the shank piece will be properly located in a shoe which is subsequently to be placed on the last. As shown in Fig. 2, the pins 20 are somewhat inclined outwardly 70 relatively to each other, even after the shank piece positioning device has been applied to the last, and the arrangement is such that when the more or less resilient shank piece is laid over the pins and pressed down against the last bottom the pins will bind in the holes in the shank piece. Thus, the pins serve not only to position the shank piece but temporarily to hold it securely in place relatively to the last. Thereafter when a shoe, which has previously been turned, is placed upon the last the shank piece will be properly positioned within the shoe and held in place until it has been secured to the shoe. The length of the pins 20 is such that the pins will not interfere with the assembling of the shank piece and the sole of the shoe in contiguous relation. The positioning device serves effectively to hold a turn shank piece 80 against edgewise displacement such as might otherwise occur during the heel-seat lasting operation. After the heel seat of the shoe has been lasted and the upper materials secured to the shank piece, the last may be withdrawn from the shoe and the shank piece positioning device will be withdrawn with the last inasmuch as the pins 18 are crimped in the holes in the last with sufficient force to 85 overcome the frictional hold between the pins 20 and the shank piece. The positioning device may be left in place on the last if the last is again to be used as a second last. When, however, it is desired to remove the device, as for example when the last is to be used as a first last, the removal of the device 90 from the last may be conveniently accomplished by inserting a suitable tool between the last and the strip 16 and prying the latter up until the pins 18 are withdrawn from the holes 10.

It will be noted that the pins 18 on the positioning device and the holes 10 in the last constitute interengaging fastening devices for detachably securing the positioning device to the last, and that the pins 20 on the positioning device and the holes 14 in the shank piece constitute interengageable fastening devices for detachably securing the shank piece in predetermined relation to the positioning device and the last. When the positioning device is detached from the last there are no special fittings on the last except the bushings 12 containing the holes 10 and these bushings and holes do not in any way interfere with the use of the last as a first last in turn shoe making or as an ordinary last for use in the manufacture of other types of shoes.

While the pins 20 on the shank piece positioning device have been herein shown and

described as being coaxially alined with the pins 18 it is to be understood that this particular arrangement of the pins is by no means essential inasmuch as the pins 20 may 5 be arranged in any convenient positions, it being necessary only that the holes in the shank piece be arranged to register with the pins 20 and that the holes in the shank piece be further arranged so that when registering 10 with these pins the shank piece will be properly positioned relatively to the last. Moreover, it is not intended, by the application of the word "pins" to the parts 18 and 20, to limit the shape or construction of these parts 15 since they may be projections of any suitable form or construction.

Having described my invention, what I claim as new and desire to secure by Letters Patent of the United States is:

20 1. A work positioning device comprising a member having a plurality of positioning projections upon one side thereof for entering holes in a piece of work to position the work in a definite angular relation to the device, and a plurality of positioning projections upon the other side of the device to enter holes in a last, said holes being spaced widthwise of the last to position the device lengthwise across the width of the last.

30 2. Means for positioning a shank piece on a last comprising a strip of sheet material adapted to be applied over the bottom face of a last, said strip having on one side thereof a pair of pins arranged to be received in holes in the last bottom to position said strip relatively to the last, and said strip having on its opposite side also a second pair of pins severally disposed in coaxial relation to the pins of the first pair and arranged to be received in holes in a shank piece to position the shank piece relatively to said strip and the last.

35 3. Means for positioning a shank piece on a last comprising a resilient member of such dimensions as to adapt it to be positioned lengthwise in transverse relation to the bottom of the heel portion of a last and having at each end portion thereof a projection constructed and arranged to be received in a hole

50 in the bottom of a last, said member being so formed as to act by its resiliency to cramp the projections in the holes in the last and having also means constructed and arranged detachably to interengage with means on a shank piece to position the shank piece relatively to said member.

40 4. Means for positioning a shank piece on a last comprising a resilient sheet metal member of such dimensions as to adapt it to be positioned lengthwise in transverse relation to the bottom of the heel portion of a last, said member having at each end portion of one side thereof a pin arranged to be received in a hole in the last bottom and being so formed 55 as to act by its resiliency to cramp the pins

in the holes in the last, said member having also a pin at each end of its opposite side arranged to be received in a hole in a shank piece to position the shank piece relatively to said member.

5. Means for positioning a shank piece on a last comprising a member adapted to be applied to the bottom of a last, said member having a plurality of projections arranged to be received in holes in the last bottom to 70 position said member relatively to the last, and said member having also a plurality of projections arranged to be received in holes in a shank piece to position the shank piece relatively to said member and the last, said 75 last-named projections being inclined relatively to each other to cause them to bind in the holes in the shank piece securely to hold the shank piece in place.

6. Means for positioning a shank piece in a shoe comprising a last, a member having positioning devices thereon adapted to engage and locate a shank piece to be applied to a shoe on the last, and interengaging fastening devices on the last and on said member, 80 said devices being spaced widthwise of the last for detachably securing said member to the last in predetermined relation thereto.

7. Means for positioning a shank piece in a shoe comprising a last having holes spaced widthwise of the last in the bottom of its heel portion, and a strip provided with means adapted to have holding engagement with a shank piece to be applied to a shoe on the last, 90 said strip having locating pins in its opposite 95 ends for entering said holes in the last to locate said strip on the last.

8. Means for positioning a shank piece in a shoe comprising a last, a strip adapted to be located between the last and the shank 105 piece, interengageable devices on the last and on said strip spaced lengthwise of the strip and widthwise of the last for securing said strip to the last in predetermined relation thereto, and a plurality of locating pins on 110 said strip adapted to enter holes formed in predetermined locations in the shank piece to position the shank piece relatively to the last.

9. Means for positioning a shank piece in 115 a shoe comprising a last having a plurality of holes in the last bottom spaced apart crosswise of the last and arranged in predetermined relation to the edge of the last bottom, a member adapted to be located between the 120 last and the shank piece, a plurality of pins on one side of said member adapted to be received within said holes in the last to locate said member relatively to the last, and a plurality of pins on the other side of said 125 member adapted to be received in holes formed in predetermined positions in the shank piece to locate the shank piece relatively to said member and to the last.

10. A device for positioning shank pieces 130

on lasts comprising a thin narrow strip adapted to extend crosswise of a last between the last bottom and a shank piece, said strip having at one side a pair of pins spaced lengthwise of the strip for entering spaced holes in the bottom of the last and having, at the opposite side thereof, a pair of pins spaced lengthwise of the strip for entering spaced holes in the shank piece, thereby to position the shank piece in a desired lengthwise, lateral and angular relation to the last.

In testimony whereof I have signed my name to this specification.
